LOOSE END ELIMINATOR

Wilbur D. Stegall, Concord, and Robert L. Bruton
and Albert J. Bartson, Charlotte, N. C.

Application June 5, 1946, Serial No. 674,622

8 Claims. (Cl. 139—261)

1

This invention relates to a loom and more especially to a loom provided with replenishing means, wherein this invention is designed for removing loose ends from an outgoing bobbin upon a transfer taking place by the moving into the shuttle of the new bobbin and the expulsion from the shuttle of the exhausted bobbin. Usually there is a feeler mechanism in a replenishing loom which detects the absence of yarn on the bobbin just before the yarn is completely exhausted from the bobbin. This feeler mechanism sets in motion a transfer mechanism, which transfers a bobbin from the magazine in a box loom or from the battery in a battery loom into the shuttle, and at the same time ejects the almost exhausted bobbin from the shuttle into a suitable can disposed below the shuttle box. Usually there occurs at the same time, a severing operation which severs the yarn near the edge of the cloth, which is wound onto the outgoing bobbin, and it is the purpose of this invention to provide means for catching and removing this end of yarn on the exhausted bobbin, and preventing its being carried back in the cloth being woven by the shuttle.

It is an object of this invention to provide in a replenishing loom, means for engaging and removing from operative position the end of yarn on an exhausted bobbin as it is being transferred from the shuttle into a suitable receptacle.

It is another object of this invention to provide in a replenishing loom, means for engaging and removing from the path of the shuttle the end of yarn on an exhausted bobbin, which is being ejected from the shuttle.

Some of the objects of the invention having been stated, other objects will appear as the description proceeds when taken in connection with the accompanying drawings, in which—

Figure 1 is a top plan view of the portion of a loom showing my invention applied thereto;

Figure 2 is a front elevation looking from the lower side of Figure 1;

Figure 3 is an end elevation looking from the right hand side of Figure 2;

Figure 4 is a top plan view of the major portion of the invention disassociated from the loom;

Figure 5 is a view partly in section and partly in elevation taken along line 5—5 in Figure 4.

Referring more specifically to the drawings, the numeral 10 indicates a loom frame having a conventional lay 11 provided with a shuttle box 12 for receiving bobbins 23. The lay is equipped with a suitable reed 15 for beating up the filling in the weaving of the cloth 16.

The loom is also equipped with a suitable

2

transfer arm 17 and a picker 18 sliding on a conventional picker rod 19, and propelled by a picker stick 20. The loom also has a conventional magazine 22 in which bobbins 23 are stored for transfer by the transfer arm 17 into the shuttle 13 disposed in the box when the detecting mechanism, not shown, calls for a transfer operation.

The loom is also equipped with a crank shaft 24 and it has a conventional rock shaft 25 having swords 26 thereon, which at their upper ends are suitably joined to the lay of the loom for imparting oscillation to the lay. Although this invention is shown as applied to a box loom, it is desired to be understood that it can operate equally as well on a battery loom having a rotary battery disposed in a suitable hopper frame.

There is also provided a suitable empty bobbin can 27 for receiving the empty bobbins 28.

On the outer end of the lay of the loom, there is provided a bracket 30, having pivotally secured thereto as at 31, an oscillating member 32, to which is secured a serrated blade 33. There is also provided on the loom a spring perch 34 to which one end of a tension spring 35 is secured, the other end of the tension spring 35 being secured, as at 36, to the serrated blade 33. Also there is pivotally secured on the blade 33, as at 40, a bracket 41, which has pivotally secured thereto, as at 42, which is a horizontal pivot, a connecting rod 43, which projects over beneath the end of the shaft 24 and is slidably mounted in an oscillating bearing 45 mounted on spring perch 24. This rod 43 has adjustably secured thereon a cam member 46, and on shaft 24 is mounted a cam 47, which is adapted to engage the cam 46 and ride upwardly on its sloping face 48 to project the rod 43 forwardly, which gives a swinging movement to the serrated blade 33. Secured to the back side of the shuttle box 12 by means of a bolt 60 is a downwardly projecting member 61 which has a leather bumper 62 secured near its lower end for limiting movement of blade 33 to prevent its striking the picker stick 20.

45 The loose end of the yarn is indicated at 51. There is provided on the lay a downwardly projecting plate 52, having serrations 53 on its lower edge for engaging the loose ends 51 and assisting in removing them from the shuttle box, since the loose ends 51 are projecting against the serrations in the lower edge of plate 52 by the moving blade 33.

Method of operation

55 Let us assume that the lay is moving upwardly

away from the operator in Figure 1, or to the right in Figure 3. This will happen while the pointed end of cam 47 is traveling through the upper portion of its circular travel. As the lay moves rearwardly, the cam block 46 moves to the right beyond the path of the block in Figure 3, and this continues until the lay has swung all the way to the back, then the lay starts moving forwardly or downwardly in Figure 1 or to the left in Figure 3, and the cam block 46 rides just in front of the pointed portion of cam 47 on the forward travel of the lay. Since the pointed cam 47 is traveling at a faster rate of speed than the block 46, its pointed end rides onto the sloping surface 48 of block 46 and imparts a quick forward motion to the connecting rod 43, which imparts a quick swing forwardly to the serrated blade 33. This happens immediately after a transfer operation and as the loom lay has reached its most forward position. The blade thus catches the end 51 and removes it from the shuttle box. The purpose of plate 52 is to prevent the end 51 from bouncing away from the blade 33. Any loose ends not entirely removed from the shuttle box by the blade 33 will be caught by the serrations on the lower edge of plate 52 and thus will be prevented from being drawn back into the cloth by an outgoing shuttle. This forward kick of the serrated blade 33 causes it to engage any fallen ends of yarn 51, which might be in its path and when the blade 33 has completed its forward swing, the tension spring 35 quickly retracts it and the member 61 is provided to limit the backward swinging movement of the blade 33 to prevent its hitting the picker stick.

In the drawings and specification, there has been set forth a preferred embodiment of the invention, and although specific terms are employed, they are used in a generic and descriptive sense only, and not for purposes of limitation, the scope of the invention being defined in the claims.

We claim:

1. In a loom having a lay and a shuttle box and means for transferring a bobbin into the shuttle box and ejecting an exhausted bobbin from the shuttle box, a blade pivotally mounted on the lay and disposed below the shuttle box, said blade having a serrated edge for engaging a strand of yarn from an ejected bobbin to prevent its being carried back into the cloth being woven by the travel of the shuttle, a link pivotally mounted at one end to the blade and having its other end slidably mounted on the loom, a driven shaft in the loom and a cam member on the driven shaft, a projection on the link adapted to be engaged by said cam member for imparting a swinging movement to the blade, to move its free end in the arc of a circle below the shuttle box, and a plate secured to the shuttle box and having its lower edge serrated and beneath which the blade swings to also engage the ends of yarn from the exhausted bobbins to also prevent their being drawn back into the shuttle box by an outgoing shuttle.

2. In a replenishing loom having a lay with a shuttle box at each end thereof, means for expelling an exhausted bobbin from a shuttle, a blade pivotally mounted on the lay and disposed below the shuttle box on the lay, the yarn extending from an exhausted bobbin upon the bobbin being transferred from the shuttle, means for imparting swinging movement to the blade, and a member mounted on the lay and extending

downwardly into close proximity to the path traveled by the blade and having its lower edge serrated to engage the loose ends from ejected bobbins to also prevent their being drawn back into the shuttle box by an outgoing shuttle.

3. In a loom having a lay provided with a shuttle box and means for transferring bobbins into the shuttle box and expelling an exhausted bobbin from the shuttle box, a blade pivotally mounted on the lay and disposed below the shuttle box and adapted to swing with the lay and having a serrated edge for engaging the yarn on a bobbin being transferred from the shuttle box in order to prevent its being carried by the shuttle into the cloth being woven, means driven by the loom for imparting a swinging movement to the blade independently of the swinging of the lay, and a member mounted on the lay and beneath which the blade swings and having its lower edge serrated to engage yarns lodged on the blade to also prevent their being drawn back into the shuttle box by an outgoing shuttle.

15 4. In a loom having a lay provided with shuttle boxes and means for transferring a bobbin into the shuttle and expelling an exhausted bobbin from the shuttle, a blade pivotally mounted on the lay and disposed below the shuttle box for engaging the ends of yarn extending from exhausted bobbins and removing them from the path of the shuttle, means driven by the loom for imparting a quick pivotal movement to the blade for engaging the ends on exhausted bobbins, and a member mounted on the lay and extending downwardly and beneath which the blade swings and having its lower edge serrated to engage yarns lodged on the blade to also prevent their being drawn back into the shuttle box by an outgoing shuttle.

20 5. Means for removing loose ends from an exhausted bobbin ejected from a shuttle in a shuttle box in a loom comprising a blade pivotally mounted below the shuttle box of the loom, and means driven by the loom for imparting swinging movement to the blade to swing it across the path of an end from an exhausted bobbin, as it falls from the shuttle box downwardly for engaging the end of yarn on the exhausted bobbin to prevent its being carried back into the cloth by the shuttle, and a member mounted on

30 50 the lay and extending downwardly and beneath which the blade swings and having its lower edge serrated to engage yarns lodged on the blade by movement of the blade.

6. In a replenishing loom having a shuttle box and means for transferring a bobbin into the shuttle and ejecting the exhausted bobbin from the shuttle, a blade pivotally mounted on the lay, and adapted to swing across the path traveled by an exhausted bobbin in its downward fall from the shuttle box, means driven by the loom for imparting swinging movement to the blade to cause it to move across the path of a falling exhausted bobbin to cause its end to be engaged and removed from the path of the shuttle in its travel in the loom, and a member mounted on the lay and extending downwardly and beneath which the blade swings and having its lower edge serrated to engage yarns lodged on the blade upon swinging of the blade and also acting to prevent said end from being drawn back into the cloth by an outgoing shuttle.

65 7. In a loom having a lay and a shuttle box and means for transferring a bobbin into the shuttle box and expelling an exhausted bobbin in the shuttle, a blade pivotally mounted on the lay and

70 75 8. In a loom having a lay and a shuttle box and means for transferring a bobbin into the shuttle box and expelling an exhausted bobbin in the shuttle, a blade pivotally mounted on the lay and

disposed below the shuttle box, means driven by the loom for swinging the blade below the shuttle box to engage exhausted fillings extending from bobbins being expelled from the shuttle box, and a member mounted on the lay and extending downwardly and beneath which the blade swings and having its lower edge serrated to engage yarns lodged on the blade and to prevent the exhausted fillings being drawn back into the cloth by an outgoing shuttle.

8. In a loom having a lay and a shuttle box and means for transferring a bobbin into the shuttle box and ejecting an exhausted bobbin therefrom, a blade pivotally mounted on the lay and disposed below the shuttle box, means driven by the loom for imparting a swinging movement to the blade below the shuttle box to engage the end of yarn from a bobbin ejected from the shuttle to prevent said end from being carried back into the cloth being woven by the shuttle, and a member mounted on the lay and extending downwardly and beneath which the blade swings and

having its lower edge serrated to engage yarns lodged on the blade upon forward movement of the blade and also preventing the yarn from an exhausted bobbin from being drawn back into the cloth by an outgoing shuttle.
